John Rogers

UNITED STATES PATENT OFFICE.

JOHN ROGERS, OF NEW CANAAN, CONNECTICUT.

DESIGN FOR A GROUP OF STATUARY.

SPECIFICATION forming part of Design No. 15,607, dated December 9, 1884.

Application filed October 2, 1884. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying drawing, forming part thereof.

10 A lady who is supposed to be an invalid is seated in a chair. Standing by her side, on her left, is a doctor, who is holding her hand and feeling her pulse. He is apparently urging his opinion of the lady's troubles, and 15 is trying to win the doctor who stands opposite, on the lady's right hand, and who has probably been brought in for a consultation,

to his view of the case, but without success, as he is indignantly buttoning up his coat and preparing to leave. He has an umbrella 20 under his left arm. A small table stands in front of him.

What I claim, and desire to secure by Letters Patent, is—

The design for a group of statuary, consisting of a lady seated in a chair, a doctor holding her left hand and feeling her pulse, and a doctor on her right hand standing behind a small table, as shown and described.

JOHN ROGERS.
